UNITED STATES PATENT OFFICE.

JASPER GANNETT, OF RUTHVEN, IOWA.

CORN-PLANTER.

SPECIFICATION forming part of Letters Patent No. 319,223, dated June 2, 1885.

Application filed August 22, 1884. (No model.)

To all whom it may concern:

Be it known that I, JASPER GANNETT, a citizen of the United States, residing at Ruthven, in the county of Palo Alto and State of Iowa, have invented a new and useful Improvement 5 in Corn-Planters, of which the following is a specification, reference being had to the accompanying drawings.

My invention has relation to wheel corn-10 planters designed to be drawn by horses; and it has for its object to provide an implement of the class referred to that shall possess superior advantages in point of simplicity, cheapness, durability, and general efficiency; and 15 the invention consists in the construction and novel arrangement of parts, as will be herein-after fully described, and particularly pointed out in the claims.

In the drawings, Figure 1 is a plan view of 20 a corn-planter embodying my improvements. Fig. 2 is a transverse vertical section on the line *xx* in Fig. 1. Fig. 3 is a vertical longitudinal section on the line *yy* in Fig. 1. Fig. 4 is an elevation of one of the seed-boxes, with 25 its front wall removed. Fig. 5 is a detail perspective view of one of the seed-disks, and Fig. 6 is a detail view of one of the scatterers. Fig. 7 is a detail view of one of the coverers.

Referring by letter to the accompanying 30 drawings, A designates the outer frame of the planter, and B the inner frame of the planter. Both of these frames are provided with boxes C, in which the axle D is journaled. The inner frame, B, is provided with a transverse 35 rail, E, grooved longitudinally in its under face to receive the axle D, and is tenoned at its ends in the boxes C of said inner frame, B. A screw is passed up through the axle D into the cross-rail E, to form the connection between the axle and rail E. Washers F are interposed between the frame A and the wheels G, and the latter revolve on the axle D. The frames A and B, when connected in this manner to the axle, become oscillating frames, the 45 journals of the axle being the pivotal points. The frame A may be provided with a driver's seat, and a lever, H, fulcrumed upon the transverse rail E, engages the rear rail of the inner frame, B, and extends forward to a curved 50 rack, I, at the front of the frame A, and is provided with a spring-actuated pin, I', which

may occupy any one of a series of holes in said curved rack I. This lever is within convenient reach of the driver, and is employed to regulate the depth of the cut of the opening-plows, 55 and to elevate them to free them from the ground when desired.

The plows J employed in this planter are shovel-plows, and they are secured to the inner frame, B, in the following manner: Directly beneath the axle D two short threaded bolts, K, are passed through holes in the side rails, L, of the inner frame, B, from the outside of said rails L, and these bolts K are provided with nuts K', which are turned upon them from their inner ends. In rear of these bolts K, through holes in said side rails, L, longer threaded bolts M are passed. Upon these bolts M sleeves N, having arms N' extending forward at right angles to said sleeves 70 at their outer ends, and shoulders N² at their inner ends on their front sides, are slipped against the inner faces of the rails L, and notches O in the upper edges of the arms N' engage the short bolts K, and the nuts K' are turned up against the arms N', to hold said arms in place. The upper ends of the plow-standards P are provided with holes, and the front edges of said standards are straight. The plow-standards P are slipped upon the 75 bolts M and moved outwardly against the inner ends of the sleeves N, the front edges of said standards at the tops of the same resting against the rear faces of the shoulders N². Nuts Q are then turned up against the 80 plow-standards and hold them firmly in place. Should the plow strike an obstruction, before the plow will break the arms N' will be released from their hold on the short bolts K, and the sleeves will turn and permit 85 the plows to pass over said obstruction. Still farther in the rear in the said rails L of the frame B are the longest bolts R, which are passed through said side rails, L, and through the seed-boxes S, which latter are held in 90 place thereon by nuts S'. The seed-boxes S are rectangular in shape in cross-section above the frame B, and are provided with sliding cover S². From their rear sides, below the rear rail of the frame B, the seed-boxes S are 95 beveled forward to their lower end nearly to a point. At the lower ends of their rectangu-

lar portions the seed-boxes S are provided with bottoms T, which extend nearly to their front walls. Above these bottoms T, in the rear walls of the seed-boxes, are transverse 5 openings T', extending entirely across said rear walls. The front walls have shorter transverse openings T''. The seed - disks U are pivoted upon the bottoms T of the seed-boxes S, their arms U' projecting through 10 the front openings, T', in said boxes, and their rear arms, U'', which are angle-arms, projecting through the rear openings, T''. The front arms, U', of the oscillating seed-disks are provided with slots V, made vertically through them, and the rear arms, U'', are provided with vertical perforations V''. The seed - cups V' consist of two holes, V'', made through each seed-disk in front of the pivotal point and at angles of about forty-five 15 degrees on opposite sides therefrom. The discharge-opening in front of the bottom T of each box S is covered by the seed-disk, and above the disk is a cut-off, W, under which the seed-cups work. This cut-off is to prevent 20 the corn from entering the seed-cups when they are beneath it, at which time they discharge the seed into the seed-tubes W' W'' below the bottoms T. The upper end of a pivoted lever, X, enters the slot V in each arm 25 U', said lever X being fulcrumed to the front of the box below the front opening. To the lower end of the pivoted levers X are pivoted the arms X' of the scatterers Y, which are secured to the front of the seed-boxes, near their 30 lower ends, by screws Y', passed through slots Y'', made in said arms X', into said boxes. The scatterers Z are in the form of hoe-blades bent back and up under the bevel of the seed-boxes. In the rear of each seed-box, but having their 35 arms A' attached to the inner faces of said seed-boxes, are the scrapers or coverers B', their arms being twisted to give the coverers the proper angle of inclination. The arms A' of said coverers are slotted at C', to receive the 40 screws E', by which the coverers are rendered adjustable to suit the depth to which the plows are set to cut by adjusting the lever in its rack. In the rear of each coverer, and secured to the outer frame, A, is a roller working in bearings 45 in forked arms of a hinged rod. These rollers follow the coverers and pack the ground upon the covered corn. The scatterers deflect the corn to opposite sides of the furrow alternately as the seed-slide is oscillated. The rear 50 arms of the seed-slides are connected by a horizontal bar, D', to which they are pivoted, and this bar D' is operated by a hand-lever, E', fulcrumed in a bracket, F', secured to the inner rear corner of one of the seed-boxes, and 55 is operated by hand. This lever may, however, be operated by any of the check-rowers that are adapted to oscillate the lever from side to side, thereby dispensing with the services of one man to operate the hand-lever. 60 65 This planter plants two rows of corn at one time.

Having thus fully described my invention, what I claim as new, and desire to secure by Letters Patent of the United States, is—

1. The combination, with the oscillating 70 frame A, secured to the axle journaled in the wheels and provided with the curved rack at its front, of the inner oscillating frame provided with the short bolts K and nuts K', the longer bolts M, sleeves N, having arms N', with 75 notches in their upper edges, near their forward ends, the shoulders N'' on the inner ends of said sleeves, the plows having their standards provided with holes near their upper ends, and the nuts Q, for securing said standards upon the bolts M against the shouldered ends of the sleeves, substantially as specified. 80

2. In a corn-planter, the frame provided with laterally-extending bolts K M, in combination with the sleeves carrying the plows and 85 journaled on the bolts M, and arms projecting forwardly from the sleeves and fitting under the bolts K, arranged and operating, whereby when the plow strikes an obstruction the arms will be released from the bolts K and work 90 downward, causing the turning of the sleeves to permit the plow to pass over said obstruction, as set forth.

3. The combination, with the seed-box having the rectangular upper portion and the forwardly-beveled lower portion, and the front and rear opening and the bottom with discharge-opening at the front side, said bottom and openings being above the seed-tubes, of the oscillating seed-slide pivoted upon said 100 bottom, and having its front and rear arms projecting through said front and rear openings, the lever pivoted to the front of the box and connected with the front arm of the seed-slide, and the slotted scatterer pivoted to the 105 front of the seed-box, connected to the lower end of the pivoted lever, and having its blade bent up along the bevel of the box under the seed-tubes, substantially as specified.

4. The combination, with the oscillating 110 frames secured upon the axle, and means, substantially as described, for operating the said frames, the plows secured to the inner frame, the seed-boxes attached to the same near the rear of the plows, scatterers attached to the 115 discharge end of the seed - boxes, coverers, also attached to the seed-boxes, and a packing-roller mounted in the outer frame in rear of the machine, as set forth.

5. In a corn-planter, the combination, with 120 the seed-boxes and their seed disks or slides, of the herein-described scatterer connected to the said disks or slides, so as to be actuated by the movement thereof, as and for the purpose set forth.

6. In a corn-planter, the combination, with the seed-boxes and their seed disks or slides, of levers attached to the latter and pivoted to the boxes, and scatterers connected to the levers, as set forth.

7. In a corn-planter, the combination, with 130 the seed-boxes and their seed disks or slides,

of levers connecting with the latter, and scatterers attached to the levers and arranged along the seed-boxes, the lower ends of the scatterers being bent back in the form of a 5 hoe-blade, as set forth.

8. In a corn-planter, the seed-boxes carrying the laterally-working scatterers and adjustable inclined coverers, as and for the purpose set forth.

In testimony that I claim the foregoing as my 10 own I have hereto affixed my signature in presence of two witnesses.

JASPER GANNETT.
